UNITED STATES PATENT OFFICE.

FRANK A. GILCREST, OF PASADENA, CALIFORNIA.

WALL-LINING.

1,371,756.

Specification of Letters Patent. Patented Mar. 15, 1921.

Application filed July 25, 1919. Serial No. 313,244.

To all whom it may concern:

Be it known that I, FRANK A. GILCREST, a citizen of the United States, residing at Pasadena, in the county of Los Angeles and 5 State of California, have invented certain new and useful Improvements in Wall-Linings; and I do hereby declare the following to be a full, clear, and exact description of the invention, such as will enable 10 others skilled in the art to which it appertains to make and use the same.

The present invention relates to linings for walls, and the like, used in building construction for insulating the walls against 15 the passage of moisture, heat, wind, and the like therethrough.

The object is to provide a wall lining including as a part thereof an infusorial earth known as diatomite which possesses insulating 20 characteristics to a high degree.

Another feature embodied in this invention is to provide a construction of lining wherein the earth may be used as a filler and held from displacement between paper 25 walls of the lining.

With these and further objects in view, as will in part hereinafter become apparent and in part be stated, the invention comprises certain novel constructions, combinations 30 and arrangements of parts as subsequently specified and claimed.

In the accompanying drawings,—

Figure 1 is a side elevation of a section of wall lining constructed according to the 35 present invention.

Fig. 2 is a transverse section taken through the same substantially on the plane indicated by line 2—2 of Fig. 1.

Fig. 3 is a longitudinal section taken 40 through the structure substantially on the plane indicated by line 3—3 of Fig. 1.

Fig. 4 is a side view of the section of wall lining constructed according to the present invention and embodying a modified form.

Fig. 5 is a transverse section taken 45 through the same substantially on the plane indicated by line 5—5 of Fig. 4.

Fig. 6 is a longitudinal section taken 50 through the modified form substantially on the plane indicated by line 6—6 of Fig. 4.

Referring to the drawing, the wall lining is provided with outer layers 10 and 11 formed of relatively stiff material such as cardboard and held in spaced relation by an

edge strip 12 of the same or like material 55 over-turned at its opposite edges against the outer faces of the layers 10 and 11 to form therewith an inclosure or casing. A body of non-conducting material is placed in the casing and preferably comprises a bulk of 60 diatomaceous earth 13 completely filling the space between the layers 10 and 11. The layers 10 and 11 are held from spreading apart under pressure of the weight of the 65 filler 13 by rows of suitably spaced apart buttons or fasteners 14 having elongated shanks passing transversely through the lining structure and with the heads thereof against the outer face of one of the layers and the over-turned extremities of the 70 shanks against the outer face of the other layer. The shanks of these buttons or fasteners 14 serve, in some measure, to retain the body of earth 13 from shifting in the casing should there be a tendency for the 75 earth to pack near the edge of the casing. The edge strip 12 extends entirely around the marginal edge portions of the casing to completely close the same, and may be held in position by an adhesive or in any other 80 desired manner. The sections of lining thus formed may be of any desired dimensions to suit the conditions under which it is to be applied, the outer layers 10 and 11 in all instances retaining a body part of the 85 diatomaceous earth of the desired thickness according to the use required.

In the modified form shown in Figs. 4, 5 and 6, the section of lining is formed, as above described, with the exception that 90 spacers 15 are employed between the layers 10 and 11 at spaced apart points, the spacers 15 preferably extending from end to end of the lining section. These spacers 15 may comprise lengths of rope, or other substance, 95 secured in place between the layers 10 by pins 16, or the like, which pass transversely through the layers and through the spacers. As shown in Fig. 4, the pins 16 may be used in as relatively small number as is required 100 to hold the spacers 15 from dislodgment. The spacers 15 form partitions within the casing against which the body of earth 13 rests to hold the earth from dislodgment. Of course, any other suitable means may be 105 employed for holding the spacers in place than as above described.

The sections thus formed are relatively

strong and are capable of supporting a substantial bulk of the non-conducting earth to insulate the walls of a building or the like against moisture, wind pressure, sound, and the passage of heat therethrough.

5 The sheets or layers 10 and 11 and the connecting strips 12 are of paper, or like material.

10 The present wall lining is preferably prepared for the market in the form of long strips after the manner of marketing the ordinary builders' paper, so that when the present improved lining is being applied to the wall of a building in the course of 15 construction it will naturally be applied with its greatest length extending horizontally. Thus the rows of fasteners 14, or equivalent parts, will effectively serve to retain the interposed earth against dislocation, 20 and there will be no tendency for the earth to become compacted, which might occur if the lining were placed vertically on the building. However, even if the lining is placed vertically the sheets 10 will ordinarily 25 retain the interposed earth in proper position since bulging of the sheets 10 and

11 is effectively prevented by the fasteners 14.

What I claim is:—

1. A wall lining comprising spaced apart 30 layers, an edge strip joining and inclosing the space therebetween, a body of diatomaceous earth interposed between the layers, and fasteners extending transversely through the layers and the body of earth for holding 35 the earth from packing between the layers and retaining the layers from bulging.

2. A wall lining comprising a section formed of layers, an edge strip connecting the layers to inclose the space therebetween, 40 a body of non-conducting material interposed between the layers, and spacers secured between the layers and extending through the earth to hold the layers from bulging and prevent the packing of the 45 earth in any one portion of the section.

In testimony whereof I affix my signature in presence of two witnesses.

FRANK A. GILCREST.
